DISPENSING DEVICE

Filed May 5, 1931

Chas. S. Garlitzo Inventor

884 Watson E. Colley Author

UNITED STATES PATENT OFFICE

CHARLES S. GARLUTZO, OF LUDLOW, COLORADO

DISPENSING DEVICE

Application filed May 5, 1931. Serial No. 535,209.

This invention relates to improvements in dispensing devices, and pertains particularly to a dispenser for elongated or cylindrical articles such, for example, as tooth-picks or 5 the like.

The primary object of the present invention is to provide a toothpick dispenser which will keep the picks entirely covered so that they will be protected from dust and dirt and 10 by means of which a single pick may be dispensed upon the actuation of an operating element of the device.

Another object of the invention is to provide a dispenser in which the article-carrying 15 receptacle may be easily and quickly opened to be recharged.

A still further object of the invention is to provide a toothpick dispenser which is of simple but strong and durable construction 20 and which may be economically manufactured.

The invention will be best understood from a consideration of the following detailed description taken in connection with the accompanying drawing forming part of this specification, with the understanding that the invention is not confined to any strict conformity with the showing of the drawing, but may be changed or modified so long as 25 such changes or modifications mark no material departure from the salient features of the invention as expressed in the appended claim.

Figure 1 is a view in front elevation of the 30 dispenser embodying the present invention;

Figure 2 is a vertical sectional view taken on the line 2—2 of Figure 1;

Figure 3 is a transverse sectional view taken on the line 3—3 of Figure 2; and

Figure 4 is an enlarged vertical sectional view through the bottom of the receptacle at the center.

Referring now more particularly to the drawing, wherein like numerals of reference 45 indicate corresponding parts throughout the several views, the numeral 1 indicates generally the receptacle in which the toothpicks or like articles are stored, while the numeral 2 indicates generally a supporting base there- 50 for.

The receptacle 1 is preferably of cylindrical cross-sectional design, altho as will be readily seen, it may be made of polygonal cross-sectional contour if desired. The bottom of the receptacle is in the form of an upright cone 55 3 which has an aperture 4 formed therethrough at the apex and exteriorly there is formed about this aperture a reinforcing sleeve 5.

The base 2 comprises a cylindrical inner portion 6 which is vertically disposed and 60 which receives in its outer end the cone-shaped lower end of the cylinder, as illustrated. The base also has an outer wall 7 which tapers downwardly and outwardly from the upper edge of the inner wall 6, 65 these inner and outer walls 6 and 7 being mounted upon a suitable bottom plate 8.

At diametrically opposite points upon the inner face of the wall 6 are the vertical tracks or rails 9, which position in guide-grooves 10 70 formed transversely of a circular weight-body 11. This weight carries upon its upper face the vertically disposed push rod or pin 12, the upper end of which is located, when the weight is in lowered position, within the 75 sleeve 5. This upper end of the rod 12 has a depression 13 formed therein and the edge of the rod or of this depression is substantially in the same plane as the edge of the opening 4.

The top of the receptacle 1 is closed by a cover 14 which is in the shape of an inverted cone which has an aperture 15 formed therethrough at the apex thereof. The lower edge of the cone 14 is integral with an annular 85 threaded flange 16 which engages about and has threaded connection with the upper end of the cylinder 1 in the manner illustrated.

Mounted upon the outer face of the cone bottom 3 of the receptacle is a pulley 17 over 90 which is passed a cord 18 which has its inner end attached to the weight 11, as indicated at 19, while the outer end extends laterally thru the base 2 and terminates in a button 20 which prevents its being pulled into the base when the weight 11 is down.

From the foregoing description it will be readily seen that when the toothpicks or any other cylindrical articles such, for example, 100 as matches, cigarettes, or the like are placed

on end in the receptacle 1, they will gravitate to the last one to the center of the receptacle to rest in the depressed end of the push rod 12.

5 When the cord 18 is pulled outwardly so as to raise the weight 11, the rod 12 will project the article upwardly and the cone-shaped top will guide the upper end thereof to the opening 15 through which it will be forced by the rod.

10 While in the description of the present device I have referred to the base structure 2 as being cylindrical and to the weight as being circular, it will, of course be understood that these parts may be made in other forms if desired, and the invention is not therefore to be limited to the particular configurations of the parts shown and described.

15 Having thus described my invention, what is claimed, is:

20 A dispenser for elongated articles, comprising a receptacle having a depending cone-like body terminating at its apex in a tubular sleeve which opens into the lower part of the receptacle, a cone-like top removably attached to the other end of the receptacle and having an aperture through its apex, said receptacle being vertically disposed, a cylindrical base member disposed beneath 25 and concentric with said receptacle, a pair of bars disposed vertically in the cylindrical base and extending throughout the length thereof; a disk weight body of a diameter substantially conforming to the interior diameter of the base and having edge slots each slidably receiving one of said bars, a push rod supported by said disk and extending vertically therefrom and having its upper end disposed in said sleeve and further having 30 its upper end recessed to receive an article in the receptacle, and means for raising said disk body to force an article upwardly from the depressed upper end of said rod through the aperture in the apex of said top.

35 40 45 In testimony whereof I hereunto affix my signature.

CHAS. S. GARLUTZO.
